UNITED STATES PATENT OFFICE.

VAUGHN E. MORRISON, OF DETROIT, MICHIGAN, ASSIGNOR OF ONE-HALF TO CARL F. BECKWITH, OF DETROIT, MICHIGAN.

FUEL ECONOMIZER.

Application filed February 24, 1919. Serial No. 278,690.

To all whom it may concern:

Be it known that I, VAUGHN E. MORRISON, a citizen of the United States, residing at Detroit, county of Wayne, State of Michigan, have invented a certain new and useful Improvement in Fuel Economizers, and declare the following to be a full, clear, and exact description of the same, such as will enable others skilled in the art to which it pertains to make and use the same, reference being had to the accompanying drawings, which form a part of this specification. This invention relates to fuel economizers for internal combustion engines, and consists of an automatically acting air valve for introducing air into the manifold between the carburetor and inlet ports of the engine, and a manual device for controlling the operation of the automatic valve. The object of the invention is to provide an inexpensive device that is adapted to introduce air into the intake manifold in varying quantities depending upon the degree of vacuum produced in the manifold, the construction being such that, under a sufficiently high vacuum, the air valve is automatically closed and automatically opening on a decrease of vacuum. Another object is to provide a device of the character stated that is adjustable whereby the device may close under various degrees of vacuum in the manifold.

In the usual internal combustion engine when the engine is idling—that is, when it is throttled down and the air intake port of the carburetor practically closed, the degree of vacuum in the intake manifold is high. To introduce air into the manifold at this time would be to increase the speed of operation of the engine which is undesired. This invention therefore seeks to provide a device for automatically introducing air into the manifold, which device is automatically closed under a predetermined degree of vacuum and that will automatically open as the throttle valve is opened and the engine speed is increased. Thus the device automatically acts entirely in accord with the desired operation of the engine. Many devices of this character heretofore in use are provided with valves which open automatically on reduction of pressure in the manifold, and the greater the reduction of pressure in the manifold the greater the opening of the valve, which is productive

of a result contrary to the desired necessary action. A further object of the invention is to provide a valve of the character set forth and means controlled by the operator whereby the valve may be cut out of operation, allowing the engine to be controlled entirely by the throttle valve as is usual; or released for automatic operation, and it is to be understood that the invention may be involved in various constructions within the limitation of the appended claims, and that the drawing illustrates only a single type of construction as an example.

In the drawings—

Fig. 1 is a diagrammatic view showing the use of the device on the intake manifold of an engine.

Fig. 2 is a vertical section of the part of the device attachable to the intake manifold showing the spring-opened valve.

Fig. 3 is a vertical section of a manually operable device for causing operation or cessation of operation of the automatic valve.

Ordinarily an internal combustion engine is controlled through operation of the throttle valve of the carburetor allowing a greater or less volume of flow of air therethrough. When the engine is throttled the air intake of the carburetor is closed to a greater or less extent and this causes an increase in the degree of vacuum in the manifold due to the fact that the piston displacement is greater in volume than may be supplied by the volume of air per unit of time flowing into the manifold under a closed throttle and the vacuum is decreased in the manifold on opening of the throttle and allowing a greater volume of flow of air per unit of time. Evidently, with a closed throttle, admission of air at such time would increase the speed of operation of the engine which is contrary to the desired effect produced by closing the throttle.

This invention seeks to provide a device for the admission of air to the intake manifold automatically controlled by the degree of vacuum in the manifold, the valve remaining open to allow the flow of air thereto during all variations in the degree of vacuum in the manifold up to a predetermined extent at which the vacuum is sufficient to close the valve. To this end therefore, the invention primarily consists of a chambered body 1 having an opening at the lower end through which air may flow and

2

provided with a valve seat 2 therein for the longitudinally reciprocable valve 3 and 4. The upper end of the valve body has a longitudinally threaded aperture to receive the 5 adjusting screw 5. This adjusting screw is provided with a longitudinal bore 6 for the stem 4 of the valve member which is reciprocable therein. This adjusting screw is provided with an elongated terminal portion 7 and about this portion, engaging the valve at the lower end and a shoulder on the screw, is a coiled compression spring 8, the tendency of which is to hold the valve 3 off from its seat. The tension of this spring 10 may be increased or decreased by turning the screw 5 into or out of the body 1 of the device predetermining the degree of vacuum required to seat the valve. A lock nut 9 is provided by means of which the screw may 15 be fixed in its adjusted position. Opening into the body above the valve seat is a conduit 10 having a threaded terminal portion for insertion in a threaded aperture provided in the manifold 11 as will be readily 20 understood from dotted lines in Fig. 2. The extent of opening of the valve 3 by action of the spring is limited by means of a pin 12 secured in a convenient portion of the device and preventing the closing of the 25 inlet end of the body or restriction of the said inlet by the valve being forced thereagainst. The device is automatically operable as is above described and without the addition of the inlet conduit 13 shown in 30 Fig. 2, and the automatic operation of the valve is as follows—Normally, due to the tension of the spring 8, the valve 3 is held open against the limit pin 12 and air is allowed to flow through the chambered body 35 1 and conduit 10 into the manifold 11 and this results in fuel economy in that air is introduced that is not passed through the carburetor and the mixture in the manifold is thus reduced in richness. The valve will 40 remain open to a greater or less extent under the varying degrees of vacuum ordinarily produced in the manifold depending upon the tension of the spring 8 and, upon a sufficiently high degree of vacuum being attained in the manifold to overcome the tension of the spring, the valve 3 is closed as 45 is shown in full lines in Fig. 2 preventing an admission of air into the manifold. The purpose of this, as is heretofore stated, is to 50 permit operation of the engine at slow speed under a closed throttle at which time an admission of air into the manifold would cause an increase in the speed of operation of the engine.

55 Preferably, the device is provided with an air conduit 13 and a valve member 14 is provided which automatically closes the mouth of the conduit and prevents the automatic operation of the valve device shown 60 in Fig. 2. This valve member 14 is pro-

vided in a case 15 having a cross aperture 16 therein with which the conduit 13 is connected. The valve has an aperture 17 adapted to register with the aperture 16 in the case by depression of the valve member 70 to the position shown in full lines in Fig. 3. A coiled spring 18 is provided at the bottom of the member 14 tending to force the said member to position shown by dotted lines and closing the aperture 16. As 75 will be understood also from dotted lines in said Fig. 3, a pin 19 is secured to the valve member 14 extending through a slot 20 in the case which limits the extent of upward movement of the valve body 14 by 80 the spring 18. Also, it is to be understood that, on depression of the valve head 14 to the position shown in full lines in Fig. 3, the lower recessed end 21 of the valve body 85 seats in the lower end of the case 15 at which limit of movement the aperture 17 through the valve 14 is in registration with the aperture 16 of the case. Normally, in the construction shown, the valve member 14 is forced to the position shown by dotted lines 90 in the drawing closing the aperture 16 and conduit 13 to flow of air, and this provides an efficient and serviceable device for controlling operation of the engine. In driving the city streets with a partially open 95 throttle, which limits the speed of travel to about ten to fifteen miles per hour, the opening of this conduit 13 to flow of air causes the engine to pick up speed without alteration of the setting of the throttle valve and, 100 if the valve member 14 is released to operation by the spring 18, the engine will immediately reduce in speed to that determined by the setting of the throttle valve 105 and thus by this arrangement a continual operation of the throttle valve is eliminated. The automatic closing of the valve 3 in the case 1 prevents an excess flow of air into the manifold when the engine is idling or 110 operating under a closed throttle.

115 For convenience in positioning the control member shown in Fig. 3, I have provided a shoulder 22 thereon intermediate its ends and the upper end is threaded to receive a threaded nut 23. The body is insertible through an aperture provided in the footboard 24 of the vehicle, the board being secured between this nut 23 and the shoulder as will be readily understood. Preferably, this valve control member is located 120 adjacent the clutch pedal extending upward through the footboard and the member 14 is controlled by the foot of the operator. Thus, when the device is in use the operator may simply rest his foot on the projecting end of the plug 14 which opens the conduit 13 increasing the speed of the engine but the moment the operator takes his foot from the said position to operate the 125 clutch, the speed of the engine is automatically 130

cally reduced, and an engine may be controlled from a low to a higher speed merely by the depression of this valve member 14 to a greater or less extent.

5 From the foregoing it is to be seen that the use of the device results in the economizing of fuel either with or without the use of the manually controlled valve member on the footboard, and that the device is 10 automatic in its operation, closing upon a certain determined high degree of vacuum and automatically opening on the lower degrees of vacuum produced in the manifold occasioned by variation in the opening of 15 the throttle valve and in fact is complementary to the operation of the throttle valve.

Having thus briefly described my invention, what I claim is—

1. A fuel economizer for internal combustion engines having an intake conduit comprising a chambered casing having an outlet opening into the air intake, a valve therein, a seat for the valve, a spring for holding the valve off its seat, a conduit connected with the intake end of the case, 25 and a foot-controlled device for the conduit

consisting of a casing attachable to the foot-board of a vehicle, the casing having an aperture therethrough with which the conduit communicates, a plunger having an aperture registerable with the said aperture in the casing, and a spring for projecting the plunger upward to close the conduit. 30

2. A fuel economizer for internal combustion engines comprising the combination 35 with the intake manifold, of a chambered casing opening into the manifold, a spring-controlled valve therein operated by a reduction of pressure in the manifold to close the valve, a conduit leading into the casing, 40 and a control device for the conduit consisting of a casing having an aperture therethrough with which the conduit is connected, a spring-controlled valve member normally tending to close the conduit, the valve 45 consisting of a reciprocable plunger adapted to be depressed to open the valve, and means for limiting the valve in its movement.

In testimony whereof, I sign this specification. 50

VAUGHN E. MORRISON.
